ATTORNEY

UNITED STATES PATENT OFFICE

BEAUFORD H. REEVES, OF NEW HAVEN, CONNECTICUT, ASSIGNOR TO RAY-SIGNS CORPORATION, A CORPORATION OF DELAWARE

REFLECTING UNIT

Application filed August 9, 1928. Serial No. 298,486.

My invention relates to reflecting units such as may be used in signs, warning signals and the like, and has particular reference to the type of these units shown in the Murray 5 reissued Patent #16,863. Units of the type therein disclosed generally comprise a glass lens having a cylindrical body with one end convex and the other end plane, a reflector disposed behind the plane end of the lens and a flat bottomed cap enclosing the plane end of the lens and the reflector. In order that these units may withstand exposure to weather without losing their brilliancy it is essential that the cap be secured to the lens 10 in such manner as to exclude all moisture and foreign matter from the surface of the reflector and the corresponding end of the lens. In my present invention I provide an effective seal between the cap and the lens which 15 prevents entry of water and other foreign matter into the interior of the cap and which is relatively inexpensive to manufacture. In order to make such a seal I utilize a soft non-fluid filling or gasket such as a soft metallic ring which I force between the wall of the cap and the surface of the lens after which I crimp or roll the upper edge inwardly to aid in swelling the sealing ring of soft metal and to retain the ring in position. 20 I also find it desirable to use a particularly formed reflector in combination with my sealing ring to assist in the sealing of the cap to the lens and in excluding moisture from the reflector.

30 A more detailed description of my invention follows and is given in connection with the drawings in which:

Fig. 1 is a vertical section through a reflecting unit constructed in accordance with my 35 invention;

Fig. 2 a section and plan view of the reflector used in the form of unit illustrated in Fig. 1, and

Fig. 3 is a section and plan of a modified 40 form of reflector.

In the form of my invention illustrated in Figs. 1 and 2, there is shown a reflecting unit comprising a lens 1 having a cylindrical body portion, a convex end and a plane end, a concave reflector 2, having a flat annular

peripheral portion or brim 3 adapted to rest against the plane end of the lens, and a flat bottomed cap 4. The outer diameter of the brim portion of the reflector is greater than the diameter of the lens and rests upon a shoulder or ledge 5 formed in the cap. The cap at its upper end is formed with a cylindrical wall 6 that surrounds the lens leaving a space therebetween, into which space there is forced, preferably under considerable 50 pressure, a soft metallic ring, 7 such as lead for instance. This filling or packing ring effectively seals the interior of the cap from the atmosphere and prevents entry of any moisture or other foreign matter. The packing gasket also secures the cap to the lens with the reflector therebetween by frictional engagement with the surface of the lens. In order to aid in swelling the packing and to retain the packing in position the upper 55 edge of the cap may be curled or crimped over the top of the packing toward the lens.

In Fig. 3, I have shown a different form of reflector 2^a in which the peripheral portion of the reflector is formed with a narrow horizontal ledge 3^a similar to the Murray patent referred to, and a cylindrical wall 3^b of proper diameter to snugly encircle the plane end of the lens. The lens, reflector and cap may be assembled, sealed and secured together in 60 the manner heretofore described.

It is apparent from the above that I have provided a tight jointure between the cap and the lens and have accomplished the same in such a manner that the cost of manufacture is reduced to a minimum by reason of the low cost of materials used and the minimum number of operations required in assembling the units.

It is obvious that changes may be made in the devices shown without departing from the spirit and scope of my invention as defined in the appended claims.

I claim:

1. A light reflecting unit comprising a lens, 95 a reflector positioned behind one end of the lens, a cap encasing one end of said lens and said reflector, the reflector abutting against the cap and the cap having an annular wall surrounding the periphery of said lens, and a 100

soft metallic filler disposed between said wall and said lens and frictionally securing said cap to said lens, the edge of the annular wall of the cap being inturned and cooperating with the filler to hold the cap and reflector against the lens.

2. A light reflecting unit comprising a lens, a reflector positioned behind one end of the lens, a cap encasing one end of said lens and said reflector, the cap and reflector having 10 opposed flanges and the cap having an annular wall surrounding the periphery of said lens, and a soft metallic filler disposed between said wall and said lens and frictionally 15 securing said cap to said lens, the edge of the annular wall of the cap being inturned and cooperating with the filler to hold the flanges of the cap and reflector in engagement and to hold the cap and the reflector against the lens.

20 3. A light reflecting unit comprising a lens, a reflector having a laterally extending flange behind one end of the lens, a cap encasing one end of said lens and said reflector, the cap 25 having a ledge engaging the flange on the reflector and an annular wall surrounding the periphery of said lens, and a soft metallic filler disposed between said wall and said lens and frictionally securing said cap to said lens, the edge of the annular wall of the cap 30 being inturned and cooperating with the filler to hold the flange of the reflector in engagement with the ledge on the cap and to hold the cap and reflector against the lens.

35 In witness whereof, I hereunto subscribe my signature.

BEAUFORD H. REEVES.
